UNITED STATES PATENT OFFICE

CLIFTON D. PETTIS, OF NEW YORK, N. Y.

BRAKE SHOE

Application filed July 5, 1928. Serial No. 290,364.

This invention relates broadly to the manufacture of cast articles adapted to have a reinforcing means embedded therein in a predetermined position, and more particularly to the manufacture of brake shoes having strips of reticulated or expanded metal inserted therein during the casting operation.

In the manufacture of brake shoes it is customary to provide a brake shoe having chilled metal sections arranged either at the ends of the brake shoe or distributed throughout the length of the shoe. Due to the difference in the characteristics of chilled and unchilled iron it is desirable in order to prevent the chilled sections from chipping and breaking away that the chilled sections be bonded with the unchilled sections so that even if the chilled sections are cracked they will not be displaced from the shoe. Such a brake shoe is disclosed in the patent to J. S. Thompson, 1,463,981, granted August 7th, 1923. Although the device disclosed in the Thompson patent provides a means for bonding the chilled and unchilled portions of the brake shoe together, it does not provide any means for anchoring or connecting the bonded section of the shoe to the reinforcing shell of the shoe. Nor does it provide any means for tying together the individual strips of reticulated metal used to bind the chilled and unchilled portions.

Therefore, in a brake shoe constructed in accordance with the Thompson disclosure if a chilled portion of the shoe cracks, it is temporarily held in place by one of the reticulated metal strips, but if after continued wear the metal strip itself breaks, the cracked portion of the shoe will become displaced. In accordance with my invention I tie the individual strips of reticulated metal together so that even if one of the strips which supports a cracked portion of the shoe should break, nevertheless the cracked portion will be held in place because the individual strips of reticulated metal are tied together.

In accordance with my invention I employ a reinforcing shell or backing for the shoe, the edges of the reinforcing shell being turned downwardly and inwardly and ex-

tending longitudinally of the shoe so that the downwardly and inwardly extending edges not only bond together the chilled and unchilled portions of the shoe, but anchor them to the reinforcing shell.

In the drawings illustrating two preferred embodiments of my invention,

Figure 1 is a top plan view of a brake shoe embodying my invention;

Figure 2 is a side elevation of the device shown in Figure 1, parts being shown in section;

Figure 3 is a bottom plan view of the reinforcing shell;

Figure 4 is an enlarged sectional view taken on the line IV—IV of Figure 2; and

Figure 5 is a modification showing a reinforcing shell having differently turned down edges from those shown in the preceding drawings.

Referring to Figures 1 to 4 of the drawings, there is shown a reinforcing shell 1 provided with the usual centrally disposed attaching lug 2 and pouring opening 3.

As shown in Figures 3 and 4, the reinforcing shell is provided with downwardly and inwardly extending edges 4 so arranged that when the shoe is cast these edges anchor the body of the shoe to the reinforcing shell. The body 5 of the shoe is composed of a plurality of chilled sections 6 arranged adjacent the ends of the shoe, the chilled sections being spaced apart by a portion of unchilled metal. In the illustrative embodiment of the invention shown in Figure 2 the shoe is provided with a chilled section at each end only, but it will be obvious that chilled sections may be arranged throughout the whole length of the body portion of the shoe if desired.

These chilled sections are bonded together by a plurality of reticulated or expanded metal strips 7 embedded in the chilled and unchilled portions of the shoe. The strips of metal are tied together by any desired means, for example, by tying them in a bundle with wires 8 which surround the strips.

By this arrangement the chilled sections are bonded to the unchilled sections by two superimposed reinforcing means which are,

first, the downturned edges 4 of the reinforcing shell and, second, by the reticulated wire strips 7. In order to maintain the reticulated metal strips 7 in place during the casting operation, and in order to still further bond the chilled and unchilled sections of the shoe to the reinforcing shell, at least one of the reticulated strips 7 is bent upwardly adjacent its ends as shown at 9 in Figure 2, or at intermediate points as well, if desired, so that its upper ends will contact with the inner surface of the reinforcing shell.

By this means when the metal is poured into the mold the reticulated metal strips are prevented from displacement by floating. By bending up the ends of the strips as at 9, it will be seen that the strips 7 are anchored to the reinforcing shell.

In Figure 5, a slightly different form of reinforcing shell provided with downwardly and inwardly turned edges is shown. Otherwise, the brake shoe is similar to that shown in Figures 1 to 4.

From the above description it will be understood that my invention provides a plurality of means arranged in superimposed planes for bonding the chilled and unchilled portions of the shoe to the reinforcing shell.

Although I have described in detail several preferred embodiments of the invention, it is to be understood that the invention is not so limited but may be otherwise embodied within the scope of the following claim:

I claim:

A brake shoe comprising a body portion and a reinforcing shell, the body portion extending continuously throughout the length of the shell and having chilled and unchilled portions bonded together by reticulated metal strips which extend continuously throughout the major portion of the body and are embedded within the body, said shell having downwardly and inwardly turned edges for anchoring the chilled and unchilled portions to the shell and to each other, at least one of the metal strips having its ends turned upwardly and contacting with the shell in order to tie the strips and chilled and unchilled portions to the shell.

In testimony whereof I have hereunto set my hand.

CLIFTON D. PETTIS.
